HAND MASSAGER

Thomas Kellogg, Mamaroneck, N.Y., assignor, by mesne assignments, to The Songrand Corp., Kansas City, Mo., a corporation of Missouri

Filed Aug. 12, 1963, Ser. No. 76,183

Term of patent 14 years

(Cl. D83—1)

The dominant features of my design reside in the portions shown in full line.

I claim:

The ornamental design for a hand massager, as shown and described.
